DESIGN FOR A DRESS ENSEMBLE

Sylvia Comolli, New York, N. Y.

Application December 8, 1937, Serial No. 73,451

Term of patent 3½ years

To all whom it may concern:

Be it known that I, Sylvia Comolli, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of the dress unit of a dress ensemble showing my new design.

Figure 2 is a rear view of the dress unit shown in Figure 1.

Figure 3 is a front view of the jacket unit of the dress ensemble.

The rear jacket portion is plain.

The characteristic feature of my design resides in the specific arrangement of the braided straps in conjunction with the crushed girdle and co-relating jacket, combined on the netted dress, as shown.

I claim:

The ornamental design for a dress ensemble, substantially as shown and described.

SYLVIA COMOLLI.
